UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,325,762.

Specification of Letters Patent. Patented Dec. 23, 1919.

Application filed February 15, 1918. Serial No. 217,302.

To all whom it may concern:

Be it known that I, JESSE A. B. SMITH, a citizen of the United States, residing in Stamford, in the county of Fairfield and 5 State of Connecticut, have invented certain new and useful Improvements in Type-Writing Machines, of which the following is a specification.

This invention relates to typewriting machines of the class in which the platen is displaceable to enable work-sheets and carbons interleaved therebetween to be straightened out for adjustment relative to the platen, as 10 set forth in the patent to Wernery & Smith, No. 1,132,055, dated March 16, 1915.

In said Wernery & Smith patent the platen is mounted on a hinged frame, whereby it is connected to the typewriter carriage, said hinge permitting the platen to be 15 displaced by swinging the frame and platen therewith upwardly, so that work-sheets, in the form of separate webs or fan-fold webs, may be straightened and moved forwardly relatively to the platen and the interleaved 20 carbon sheets moved rearwardly out of interleavement with the leading form of a plurality of successive forms printed upon said webs. After the leading form is moved to a 25 gage, and the platen is returned to its normal position, the leading form is severed from the web, and the typing of the next 30 form is begun. During the typing or writing operation, this hinged platen frame is 35 locked in working position by means of a latch.

The typewriting mechanism is of the usual Underwood type, and is provided with the usual appurtenances including a line-spacing mechanism for moving the platen and 40 work-sheets thereon to several writing lines or line-space positions, and a detent for holding said platen in any of its several positions against accidental displacement.

An object of this invention is to provide 45 improved means for controlling, against accidental displacement, a record-sheet for receiving carbon duplicates of items that are typed upon the web forms, a carbon being provided between said webs and record-sheet 50 and controlled in a manner similar to those interleaved between the webs. This record-sheet is commonly known as a condensed

record-sheet, the items appearing thereon in close succession, a single page containing the copies of items upon a large number of 55 forms or pages of the web.

To move the platen and the work thereon to present a new writing surface to the type and the writing point, the line-spacing mechanism is connected to the platen by 60 means of gearing as in said Wernery & Smith patent. When the platen is swung upwardly for straightening said webs a planetary motion is imparted thereto, due to the gear which is joined to the platen axle 65 being rotated about a common pinion therebetween and a gear connected to the line-spacing mechanism, which is held against rotation by said platen detent. In other words, the platen when being displaced is 70 needlessly caused to rotate about its axis, otherwise than by the line-spacing mechanism.

I have found it advantageous to positively hold said platen against rotation during said 75 displacing or swinging operation when a record-sheet is used in the machine, so as to avoid moving said record-sheet relatively to the writing point. For this purpose, I have provided a latch which is normally ineffective 80 to permit the performance of line-spacing operations when the platen is in writing position, and to hold the platen positively against rotating relatively to the writing line and the swinging frame when displaced 85 for adjustment of the webs. Said latch operates with a clamp provided for holding the record-sheet to the platen and illustrated and described in the application of Daniel F. Glackin, Serial No. 208,400, filed December 22, 1917. 90

The platen being thus locked against angular displacement, said clamp is arranged to form a gage whereby the record-sheet may be placed on the platen so that the first 95 writing space thereon will lie at the writing point. This may be accomplished by inserting the record-sheet when the platen is displaced and advancing said sheet until stopped by the gage. The platen may then 100 be replaced and, being held against rotation, will preserve the adjustment of the record-sheet relative to the platen.

I have also found it advantageous to pro-

vide a guide, whereby the record-sheet may be guided to the clamp to extend behind a front paper-table over which the webs may pass, said clamp being located at the rear of 5 said guide and paper-table and the leading edge of the record-sheet passed between the clamp and the platen.

Other features and advantages will hereinafter appear.

10 In the accompanying drawings,

Figure 1 is a fragmentary perspective view of a portion of an Underwood fan-fold typewriting machine, showing the invention applied thereto.

15 Fig. 2 is a diagrammatic sectional side view, showing the position of the parts when the platen is in writing position, some of the parts being broken away to show the underlying structure.

20 Fig. 3 is a view similar to Fig. 2, showing the position of the parts just after the platen is released preparatory to displacing it for straightening out the webs and carbons, and just as the record-sheet is clamped against 25 the platen.

Fig. 4 is a diagrammatic side view with some of the parts broken away to show the underlying structure, and showing the platen displaced for straightening out the webs, 30 and the record-sheet-clamp and platen-holding-latch in effective position.

35 Fig. 5 is a fragmentary detail perspective view, showing a portion of the record-sheet-guide, the record-sheet-clamp and platen-holding-latch and the controlling mechanism therefor.

Fig. 6 is a fragmentary sectional view, showing the mechanism for guiding the record-sheet to its clamp.

40 To perform typewriting, there is provided a typewriter framework 10 and a typewriter carriage 11 mounted for lateral movement on rails of the framework. On the carriage 11 is hinged at 12 a swingable platen frame 13, in which is journaled a platen axle or shaft 14 having fast thereon a revoluble platen 15. Mounted at the rear of said typewriter carriage 11, and adapted to travel therewith is a subsidiary carriage 16 supported at the rear on a rail 17 and having a carbon-carriage 18 mounted thereon, slideable forwardly and rearwardly along rails 19 on said subsidiary carriage 16. The carbon-carriage 18 is provided with blades 20, 50 carrying carbon sheets 21 interleaved between webs 22, the uppermost blade 20 and its carbon sheet being arranged to lie between said webs 22 and a record-sheet 23 (Fig. 1).

60 The webs and record-sheet are guided over a paper-shelf 24 (Fig. 2), arranged on the carriage 11 at the rear of the platen, and are then led under the platen over feed-rolls or pressure-rollers 25 mounted on the type-

writer carriage 11. The webs and record-sheet are then led around the platen past the printing point and under a severing knife 26 swingably mounted and controlled by a handle 27 on a rock-shaft 28, and having the usual appurtenances therefor, as illustrated 70 and described in the patent issued to J. A. B. Smith, No. 1,287,716, and dated August 21, 1917.

In order to actuate the platen for line-spacing, there is provided a handle 31 of a line-spacing or paper-feed mechanism indicated in general at 32 (Fig. 1), including a gear or ratchet wheel 33 journaled in the framework of the typewriter carriage 11, and having a detent roller 34 at the free end 75 of an arm 35 pivoted at 36 to the carriage. The roller 34 is urged against said ratchet wheel by a spring 37 to prevent overthrow of the platen 15 by the actuation of the line-spacing mechanism and to hold the platen 80 against accidental displacement in any of its several line-space positions through the intermediary of mechanism presently to be described.

The ratchet wheel 33 is fast on a shaft 40 90 journaled on the carriage 11, and is included in a train of gearing to the platen. The shaft 40 has a gear-wheel 41 mounted at the right end thereof, concentrically with the platen, when the latter is in normal or writing position. The gear-wheel 41 is in mesh with a pinion 42, revolvably mounted on the hinge 12, said pinion being in mesh with a gear-wheel 43 which is fast on the left end 95 of the platen axle 14 and is adjacent to, and concentric with, the gear-wheel 41 when in normal position. It will be seen that at the actuation of the line-spacing mechanism 32, the ratchet-wheel 33 will be actuated, and, through the intermediary of the shaft 40, 100 gear-wheel 41 and pinion 42 actuate the gear-wheel 43, and therewith the platen 15 synchronously, the pinion 42 being of sufficient width to extend across both of the gear-wheels 41 and 43. 110

The platen 15 is normally held in writing position by latch-hooks 48 (Figs. 1, 2 and 3), engaging pins 49 fast on the platen frame 13, the hooks 48 being mounted on a rock-shaft 50 actuated by a spring 51 (Fig. 1), 115 and provided with a handle 52, at the depression of which the hooks 48 may be swung clear of the pins 49 to release the platen. At this time, the platen frame 13 may be swung upwardly about its hinge 12 to a position 120 shown in Fig. 4, in which the webs 22 are shown sufficiently straightened so that the leading edges thereon may be pulled forwardly against a gage 55 mounted on an extension 56 on a front paper-table 57 which is a part of the platen frame 13. As the webs are thus adjusted, the carbons 21 may be retracted so as to lie interleaved with a 125

succeeding form on the webs and so that their leading edges will be clear of the severing knife 26, by thrusting rearwardly a handle 60 fast on the carbon-carriage 18 to move said carriage and carbons thereon rearwardly along the rails 19 until the leading edges of said carbon sheets may lie between the writing point on the platen and the severing edge of the blade or knife 26, as in Fig. 2, when the platen is restored to its normal writing position, after which the typewritten forms of the webs may be severed, and a succeeding form may be type-written upon.

15 The mechanism thus far described is of a type commonly known as the Underwood fan-fold type of machine, and is of a form substantially as illustrated and described in said Wernery & Smith patent.

20 It is advantageous to hold the record-sheet 23 against displacement when the webs 22 are advanced, or otherwise adjusted, so as to hold said record-sheet fixed relatively to the writing line on the platen, and 25 so as to afford a condensed record of the items typed upon the webs.

For this purpose, there is provided a paper-clamp 65 in the form of a bar or rock-shaft journaled at 66, Figs. 1 to 5, at 30 either side of the swingable frame 13. The clamp 65 has a flat surface 67 formed thereon, Fig. 5, extending the entire length of the platen and in close proximity thereto, to afford sufficient space therebetween and the 35 platen when said clamp is opened, to permit the passage of one or more record-sheets 23. This form of paper-clamp is illustrated and described in said application, Serial No. 208,400. The clamp 65 is normally in ineffective position and is positively held in 40 that position by a lever 68 fast near the left end thereof, Figs. 1 to 5. Said lever extends rearwardly and is cam-shaped at its free end as at 69, Fig. 5, and normally bears 45 against the rear paper-shelf 24, when the platen and associated parts are in their normal positions.

To close the clamp and to hold the lever to the paper-shelf 24, there is provided a 50 spring 70, Figs. 1 to 5, which constantly urges the clamp to effective position, as seen in Figs. 3 and 4. One end of said spring is attached to a pin 71 fast on the swingable frame 13; and the other end is 55 connected to an extension 72 of the lever 68 which extends in an opposite direction thereto, to urge the clamp 65 and lever 68 in counter-clockwise direction, so that the rear edge of the surface 67 will be moved 60 to clamp the record-sheet 23 to the platen 65 when said spring is released.

It is advantageous when placing a record-sheet 23 into the machine to guide the leading edge of said record-sheet to the clamp.

For this purpose, there is provided at the 65 lower end of the front-paper-table 57 a guide 75 in the form of an extension of said table, Figs. 1 to 5, arranged so as to extend into the path of the record-sheet 23, in such a manner as to guide and deflect the 70 leading edge of said record-sheet when inserted into the machine so as to pass behind the paper-table 57 while the webs 22 may pass in front thereof. The record-sheet is preferably inserted when the platen frame 75 13 is in its abnormal or Fig. 4 position, with the webs 22 in the Fig. 4 and Fig. 6 position, at which time the record-sheet may be inserted at the introductory side of the platen, and the leading-edge thereof guided 80 to wedge into the bight of the clamp and the platen by the guide 75 and by an auxiliary guiding portion 76, Fig. 6, contiguous with the guide 75 and formed on the rock shaft 28. This will place the record-sheet 85 so that the portion thereof first to be written upon will be brought to the writing line along the platen.

If it is desired to advance the record-sheet beyond the clamp, the clamp may be 90 opened by actuating the lever 68 manually against the tension of the spring 70, and by manually adjusting the sheet 23 to the desired position. The platen may then be returned to its normal writing position and 95 automatically locked in place by the latches 48, and the clamp 65 automatically moved to ineffective position, thereby releasing the record-sheet for line-space feeding thereof. When thus returning the platen the lever 68 100 strikes against the paper-shelf 24, which, co-acting with its cam 69, swings the clamp 65 in clockwise direction against the tension of its spring 70 to release the record-sheet 23 and to permit said record-sheet and webs 105 22 to be advanced in unison in line-spacing direction when the line-spacing mechanism 32 is actuated.

It will be noted that said clamp 65 is adapted to detain a work-sheet of any width 110 within the capacity of the machine, and to clamp said sheet in any position along the platen without any special adjustment of the clamp or associated parts being required for this purpose.

115 It will also be noted that it is advantageous to actuate the line-space handle 31 prior to releasing the platen from its normal position after typing has been performed on the record-sheet 23, to move the 120 last line of writing thereon away from the writing line of the platen, so that the first line of writing of a succeeding form will not overlie the said last line of writing on the record-sheet. This result may also be obtained by actuating the line-spacing mechanism 125 after the platen has been restored to its normal position subsequent to a writing

and severing operation, the printed forms on the webs and the gage 55 being adjusted accordingly.

It will be seen by reference to said Werner & Smith patent and to said Glackin application, that the platen 15 is subject to a planetary motion when being swung from and to normal position, and that in said Glackin application the spring-actuated roller-detent which co-operates with the line-spacing mechanism is manually silenced when the platen frame is swung for adjustment to avoid the rotative movement of the platen on its axle.

I have found it advantageous to overcome said planetary motion or rotative movement by automatically detaining the platen against angular movement about its shaft 14 when the platen is swung out of its normal position, so as to insure the record-sheet 23 against any accidental displacement whatsoever. Said angular movement of the platen 15 about its shaft 14, when being displaced, is caused by the gear wheel 43 being bodily swung about the hinge 12 while in mesh with the pinion 42 which is being held stationary by the spring-pressed detent 34, 35, through the intermediary of the gear wheels 33 and 41. This swinging of the platen will cause a clockwise rotation of the platen when swung from its normal position, and a counter-clockwise rotation of the platen when returned to its normal position.

To overcome this planetary motion, there is provided a latch, indicated in general at 78, mounted on the swingable platen frame 13, to slide thereon radially of the platen into effective position when the platen is displaced, and into mesh with the gear wheel 43 to positively hold the platen against rotation. To guide the latch 78 in its movement into and out of effective position, there is provided at its upper end a slot 79, Figs. 1 to 5, in engagement with a pin 80 fast on the platen frame 13, and arranged to guide and retain the upper end of said latch. The lower end of the latch 78 is guided by a fork 81 straddling a collar 82 on the platen shaft 14, and is held against lateral displacement by projections 83, said projections being adapted to extend in the space between the gear wheel 43 and the left end of the swingable platen frame 13.

To urge the latch 78 to effective position, there is fast thereon a pin 86, Figs. 2, 3 and 5, to which is attached one end of a spring 87, the other end of which is attached to a pin 88 fast on the platen frame 13, said spring being so arranged as to draw said latch 78 inwardly, so that a tooth or detent 89 thereon, normally extending above the gear wheel 43, may be drawn into the path of said gear wheel and between the teeth thereof when said latch is released, to positively connect said gear wheel to the platen

frame 13 to prevent any rotation of said gear wheel and the platen relative to said frame, Figs. 3 and 4, thereby causing the platen to swing in unison with said frame and not to move relatively thereto.

To hold the latch 78 in its normal ineffective position with the tooth 89 thereof out of engagement with the gear or rack 43, there is provided a connection between said latch and the clamp 65, whereby said latch is controlled by said clamp.

For this purpose, there is fast at the left end of the clamp or rock-shaft 65 an arm 92 placed without the frame 13 and extending rearwardly, so that its free end underlies an offset 93, Figs. 1 to 5, formed on the latch 78. The latch 78, arm 92 and clamp 65 are so arranged that when the clamp 65 is positively held in ineffective position by the lever 68 co-acting with the paper shelf 24, the latch 78 will also be positively held in ineffective position against the tension of its spring 87, but when said lever 68 is released, the arm 92 will swing downwardly in counter-clockwise direction with the cam 90, thereby releasing the latch 78 to permit the spring 87 to draw the tooth 89 thereof into mesh with the gear wheel 43, said gear wheel being so arranged that a tooth space thereon will lie opposite the tooth 89 when the platen 15 is in any of its several line-space positions, the parts being so arranged that said engagement will take place prior to any planetary rotation of the platen 15 and will prevent such rotation.

It will be noted that the clamp 65 may be closed by the latch spring 87 through the intermediary of the offset 93 and arm 92, but it is advantageous to provide auxiliary actuating means for said clamp since greater care will be required with a single actuating means in adjusting said clamp and said tooth relatively to its gear, particularly when record-sheets 23 are employed of such thickness that only a slight movement of the clamp 65 will be required to hold the sheets to the platen. This amount of movement may, under abnormal conditions, be insufficient for effecting a complete engagement of the tooth 89 with the gear wheel 43. If the parts are adjusted to the use of very thick record-sheets 23, the tooth 89 may move to its extreme inward position before the clamp 65 becomes effective in case a thin record-sheet is used.

Any fault in this direction could easily be overcome by the employment of deep tooth spaces on the gear wheel 43 and little clearance between the detent 89 and said gear wheel. With this construction a slight movement of the clamp 65 and latch 78 will serve to lock the platen 15 when a greater thickness of record-sheets are used, and will permit a long stroke of the slide or latch 78 when a thin record-sheet 23 is used.

It will be noted that the latch 78 when in effective position holds the platen 15 and work-sheets 22, 23 against angular displacement by the accidental actuation of the line-spacing mechanism 32 or the platen handles or knobs 94.

It will also be noted that when a record-sheet 23 is not completely used up when the webs 22 are used up or a new web is to be 10 inserted into the machine for other reasons, the clamp 65 will hold the record-sheet 23 against displacement when the webs 22 are withdrawn from the machine, and that a new set of webs 22 are inserted thereinto, so 15 that a record of items typed upon new web forms may be copied on the record-sheet 23, without any break in the continuity of the writing thereon.

Variations may be resorted to within the 20 scope of the invention, and portions of the improvements may be used without others.

Having thus described my invention, I claim:

1. In a typewriting machine, the combination with a revolute platen, of a displaceable support for said platen, normally ineffective means to hold a work-sheet against the platen, and means, normally ineffective, for holding the platen against 25 rotation relative to its support.

2. In a typewriting machine, the combination with a revolute platen, of means for displacing said platen bodily, a normally-ineffective clamp, means for rendering said clamp effective to hold a work-sheet when 30 said platen is displaced, and means, operatively connected with said clamp, for holding the platen against rotation relative to said clamp.

3. In a typewriting machine, the combination with a revolute platen, of means for swinging said platen bodily, a normally-ineffective clamp, means for rendering said clamp effective to hold a work-sheet when 45 said platen is swung, and means for holding said platen against rotation relative to said clamp.

4. In a typewriting machine, the combination with a revolute platen and a movable platen frame to enable the platen to be moved from its normal position to an abnormal position, of means, normally ineffective, for holding a work-sheet to prevent displacement thereof relative to the 50 platen when the latter is moved from its normal position, means for holding the platen against rotation, relative to said platen frame, when moved from its normal position, and means for releasing both of 55 said holding means when the platen is returned to its normal position.

5. In a typewriting machine, the combination with a revolute platen and means for feeding a record sheet, a web and an interleaved carbon sheet thereabout, of means, 60

including a swinging platen-support, for moving said platen away from said feeding means to enable adjustment of said web and carbon sheet, a normally ineffective clamp for holding said record sheet against said 70 platen, a normally ineffective means for holding the platen against rotation relative to said support, and means controlled by said swinging means for rendering said clamp and platen-holding means effective.

6. In a typewriting machine, the combination with a revolute platen and means, including a platen frame, for displacing said platen from its normal position, of means to feed a record sheet, webs and interleaved carbon sheets about said platen, a normally ineffective clamp to hold said record sheet against the platen, controlling 75 means to render said clamp effective, a normally ineffective means for holding said platen against rotation with respect to the platen frame, and a connection between said clamp-controlling means and said platen-holding means, whereby said clamp and said platen-holding means will be rendered 80 effective and ineffective concomitantly.

7. In a typewriting machine, the combination with a revolute platen and a movable platen frame to enable displacement of said platen from its normal position, of means to support work-sheets in engagement with the platen when said platen is in normal position, a clamp movable to position to retain a work-sheet against the platen, means urging said clamp to effective position, means, including a latch, for holding said platen against rotation relative to said frame, means urging said latch to effective position, means effective when said platen is in normal position to retain said clamp 90 and latch in ineffective positions, and releasable means to retain said platen frame in normal position and thereby maintain both said clamp and said latch in ineffective positions.

8. The combination with a revolute platen, means for supporting work-sheets and interleaved carbon sheets in engagement therewith, and a frame upon which the platen is mounted for displacement from said supporting means to permit straightening and relative adjustment of said work-sheets and carbon sheets, of a clamp mounted upon said frame to hold a work-sheet against the platen, and means for positively holding the 95 platen against rotation, relative to said frame, when displaced.

9. The combination of a revolute platen, a swinging frame upon which it is mounted for swingable displacement, a clamp upon said frame to hold a work-sheet against the platen, means to press said clamp against the platen, means for retaining said clamp in ineffective position, means rendered effective upon swinging said frame 100 120 115 125 130

- from normal position for holding said platen against rotation on said frame, and means, brought into action by the swinging of said frame, to render said retaining means effective and permit said clamp to press the work-sheet against the platen. 5 feed rolls, a paper shelf in the rear of said platen, a clamp for holding a work-sheet against said platen, a spring normally tending to make said clamp effective to hold the work-sheet, and a lever on said clamp co-operating with said paper shelf to move the clamp to ineffective position when said platen and said feed rolls are brought together to enable said latch to become effective. 65
10. The combination of a revoluble platen, means to maintain work-sheets and carbons in engagement with said platen when the latter is in normal position, a movable frame upon which the platen is mounted for displacement to permit straightening and relative adjustment of work-sheets and carbons, means mounted upon said frame to hold a work-sheet to the platen, means upon said frame for holding the platen against rotation, and means for automatically rendering said sheet and platen-holding means effective. 70
15. The combination of a revoluble platen, means to maintain work-sheets and carbons in engagement with said platen when the latter is in normal position, a movable frame upon which the platen is mounted for displacement to permit straightening and relative adjustment of work-sheets and carbons, means mounted upon said frame to hold a work-sheet against the platen, means on said frame for holding the platen against rotation, and means for automatically rendering said sheet and platen-holding means effective, and for automatically restoring said sheet and platen-holding means to ineffective position. 75
20. The combination of a revoluble platen, means to maintain work-sheets and carbons in engagement with said platen when the latter is in normal position, a movable frame upon which the platen is mounted for displacement to permit straightening and relative adjustment of work-sheets and carbons, means mounted upon said frame to hold a work-sheet against the platen, means on said frame for holding the platen against rotation, and means for automatically rendering said sheet and platen-holding means effective, and for automatically restoring said sheet and platen-holding means to ineffective position. 80
25. In a typewriting machine, the combination with a revoluble platen, of feed rolls co-operating therewith, means, including a swinging platen-support, for swinging said platen away from the feed rolls to enable work-sheets to be adjusted relatively to the platen, means, including a latch, normally holding said platen to the feed rolls, means for holding work-sheets against the platen, means, normally ineffective, to hold the platen against rotative displacement relative to said platen-support, and means for rendering said sheet-holding means effective by releasing said platen to swing it away from said feed rolls. 85
30. In a typewriting machine, the combination with a revoluble platen, of feed rolls co-operating therewith, means, including a latch normally holding said platen to the feed rolls, means for holding a work-sheet against the platen, a paper shelf at the introductory side of the platen, and means, including a lever co-operating with said paper shelf, to render said holding means ineffective when said latch is in normal position. 90
35. In a typewriting machine, the combination with a revoluble platen, of feed rolls co-operating therewith, means, including a latch normally holding said platen to the feed rolls, means for holding a work-sheet against the platen, a paper shelf at the introductory side of the platen, and means, including a lever co-operating with said paper shelf to move the clamp to ineffective position when said platen and said feed rolls are brought together to enable said latch to become effective. 95
40. In a typewriting machine, the combination with a revoluble platen, of feed rolls co-operating therewith, means, including a latch normally holding said platen to the feed rolls, means for holding a work-sheet against the platen, a paper shelf at the introductory side of the platen, and means, including a lever co-operating with said paper shelf to move the clamp to ineffective position when said platen and said feed rolls are brought together to enable said latch to become effective. 100
45. In a typewriting machine, the combination with a revoluble platen, of feed rolls co-operating therewith, means, including a latch normally holding said platen to the feed rolls, means for holding a work-sheet against the platen, a paper shelf at the introductory side of the platen, and means, including a lever co-operating with said paper shelf to move the clamp to ineffective position when said platen and said feed rolls are brought together to enable said latch to become effective. 105
50. In a typewriting machine, the combination with a revoluble platen, of feed rolls co-operating therewith, means, including a latch normally holding said platen to the feed rolls, means for holding a work-sheet against the platen, a paper shelf at the introductory side of the platen, and means, including a lever co-operating with said paper shelf to move the clamp to ineffective position when said platen and said feed rolls are brought together to enable said latch to become effective. 110
55. In a typewriting machine, the combination with a revoluble platen, of feed rolls co-operating therewith, means, including a latch normally holding said platen to the feed rolls, means for holding a work-sheet against the platen, a paper shelf at the introductory side of the platen, and means, including a lever co-operating with said paper shelf to move the clamp to ineffective position when said platen and said feed rolls are brought together to enable said latch to become effective. 115
60. In a typewriting machine, the combination with a revoluble platen, of feed rolls co-operating therewith, means, including a latch normally holding said platen to the feed rolls, means for holding a work-sheet against the platen, a paper shelf at the introductory side of the platen, and means, including a lever co-operating with said paper shelf to move the clamp to ineffective position when said platen and said feed rolls are brought together to enable said latch to become effective. 120
65. In a typewriting machine, the combination with a revoluble platen, of feed rolls co-operating therewith, means, including a latch normally holding said platen to the feed rolls, means for holding a work-sheet against the platen, a paper shelf at the introductory side of the platen, and means, including a lever co-operating with said paper shelf to move the clamp to ineffective position when said platen and said feed rolls are brought together to enable said latch to become effective. 125

ing a latch, for holding the platen against rotation when in web-adjusting position, means, controlled by said locking means and including a lever connected with said clamp, for holding said clamp in ineffective position, and means whereby the position of said latch will be controlled by the position of said clamp, release of said locking means enabling concomitant movement of said clamp and said latch to their effective positions.

19. The combination with a revoluble platen, and means to maintain work-sheets and carbons in operative engagement with said platen when the latter is in its normal position, of a frame upon which said platen is mounted for displacement to permit straightening and relative adjustment of work-sheets and carbons, a clamp mounted in said frame for holding a work-sheet to the platen, and means, including a latch slidably mounted on said frame, for positively holding the platen against rotation relative to said frame when the latter is displaced.

20. The combination with a revoluble platen and feeding means to maintain work-sheets and carbons in operative engagement with the platen when the latter is in normal position, of a frame upon which the platen is mounted for displacement to permit straightening and relative adjustment of work-sheets and carbons, a clamp effective along the entire length of said platen to hold a work-sheet against the platen, and means, including a latch at one end of said clamp and coöperating therewith, for positively holding the platen against rotation relative to said frame when the latter is displaced.

21. The combination with a revoluble platen, and work-sheet-guiding means with which it coöperates while in normal position, of a frame upon which the platen is mounted for displacement to permit straightening and relative adjustment of work-sheets and carbons, a clamp in the form of a bar mounted upon said frame for holding a work-sheet to the platen, means, including a latch slidably mounted on said frame, for holding the platen against rotation, and means for automatically rendering said clamp and latch effective and ineffective.

22. The combination with a revoluble platen, and work-sheet-guiding means with which it coöperates while in normal position, of a frame upon which the platen is mounted for bodily displacement to permit straightening and relative adjustment of work-sheets and carbons, means upon said frame for holding the platen against rotation, and means for automatically rendering said platen-holding means effective.

23. The combination with a revoluble platen, and work-sheet-guiding means with which it coöperates while in normal position, of a frame upon which the platen is mounted for displacement to permit straightening and relative adjustment of work-sheets and carbons, means upon said frame for holding the platen against rotation, means for automatically rendering said platen-holding means effective when the platen is displaced, and means for automatically rendering said platen-holding means ineffective when the platen is replaced.

24. In a typewriting machine, the combination with a revoluble platen, of means, including a movable platen frame, whereby the platen may be moved from its normal position, normally ineffective locking means adapted to lock said platen against rotation relative to said frame, means for actuating said platen, including a ratchet wheel, driving connections between said ratchet wheel and said platen whereby displacement of said frame will tend to effect relative rotation between said ratchet wheel and said platen, a yieldable detent for preventing accidental displacement of said ratchet wheel, and means for locking said platen against rotation relative to said platen frame, the yieldable detent being overcome by said locking means when said frame is displaced.

25. In a typewriting machine, the combination with a platen, feeding means to maintain a record sheet, webs and carbons in operative engagement with said platen when the latter is in normal position, and means, including a movable platen frame, for displacing said platen, of normally effective feed rolls arranged at the introductory side of the platen for feeding said webs and record sheet, a normally ineffective clamp at the delivery side of the platen for holding said record sheet to the platen when the platen is displaced, means, including a normally ineffective latch, for holding said platen against rotation relative to said frame during displacement of the latter, and means for simultaneously rendering said feed rolls ineffective and said clamp and latch effective.

26. In a typewriting machine, the combination with a revoluble platen, of paper-feeding devices including a pressure roll, means for releasing work-sheets from the control of the pressure roll, and a normally ineffective paper clamp and a platen-detaining latch actuated by said releasing means, said clamp and platen latch being moved to effective positions by the same movement that releases the work-sheets from the control of the pressure roll.

27. In a typewriting machine, the combination with a revoluble platen, of a feed-roll at the introductory side of the platen,

- 5 a normally-ineffective work-sheet clamp at the delivery side of the platen, a normally-ineffective platen-detaining device at one side of the platen, and means for simultaneously moving the platen away from said feed-roll and causing the work-sheet clamp and platen-detaining device to become effective.
- 10 28. In a typewriting machine, the combination with a revoluble platen, of means for feeding work-sheets to and around said platen, a clamp for a work-sheet ineffective during the paper-feeding operation, and means for locking the platen, effective when 15 said clamp is in effective position.
- 15 29. In a typewriting machine, the combination with a revoluble platen normally locked in writing position and displaceable for adjustment of work-sheets relatively 20 thereto, of a lever for unlocking said platen, line-spacing mechanism, a normally-ineffective clamp through which a work-sheet is fed, a normally-ineffective latch connected to said clamp for holding the platen against 25 rotation, and means, including connections between said lever and said latch and clamp, whereby an unlocking movement of said lever will cause said clamp and said latch to be moved to effective positions.
- 30 30. In a typewriting machine, the combination with a platen, of a train of gearing for actuating said platen, means for displacing said platen bodily, and a latch coöperating with said gearing for positively holding 35 said platen against angular movement.
- 35 31. In a typewriting machine, the combination with a platen, of a gear wheel joined to the platen, means for displacing said platen bodily, and a latch coöperating with 40 said gear wheel for positively holding said platen against angular movement.
- 40 32. In a typewriting machine, the combination with a revoluble platen, of means for displacing said platen bodily, platen-actuating 45 means adapted to yieldingly urge said platen to rotate during the platen-displacing movement, and means for positively holding said platen against angular movement by said platen-actuating means during the displacing movement of said platen.
- 45 33. In a typewriting machine, the combination with a revoluble platen, of a swingable frame for displacing said platen bodily, a normally-ineffective clamp adapted to hold 50 a work-sheet to the platen when the latter is being displaced, means, including a normally-ineffective latch on said frame, for holding the platen against rotation, a spring for moving said latch to effective position, 55 and an arm on said clamp for moving said latch to ineffective position when the clamp is moved to ineffective position.
- 60 34. The combination with a revoluble platen, of a frame upon which it is mounted for displacement to permit straightening 65 and relative adjustment of work-sheets and carbons, a clamp in the form of a rock-shaft journaled in said frame in close proximity to said platen for holding work-sheets to the platen, and means, including a latch on said frame adapted to move radially of the platen, for positively holding the platen against rotation when displaced.
- 65 35. The combination with a revoluble platen and a platen frame for displacing 70 said platen bodily, of a carriage on which said frame is mounted, mechanism for line-spacing the platen including a ratchet wheel on the carriage, a gear wheel on the platen frame, and connections between said wheels 75 whereby a relative rotation therebetween will be effected by displacement of said platen, a spring detent coöperating with said ratchet wheel for holding said platen at any line-space position, and normally-ineffective 80 means coöperating with said gear wheel for positively holding said platen against displacement by said line-spacing mechanism, said platen-holding means being adapted to overcome said detent.
- 80 36. In a typewriting machine, the combination with a revoluble platen, of a work-sheet on said platen, a normally-ineffective clamp for holding said work-sheet to the platen, means, including a normally-ineffective 85 latch, for holding the platen against angular movement, and means for holding said clamp and latch against accidental displacement from ineffective position.
- 85 37. In a typewriting machine, the combination with a platen, of paper-feeding mechanism for feeding webs and a record-sheet to and around the platen, a clamp for holding said record-sheet to the platen, a paper-table at the delivery side of the platen for said 90 webs, and a guide at the lower end of said paper-table for guiding said record-sheet to the clamp.
- 90 38. In a typewriting machine, the combination with a revoluble platen, of a frame 100 for displacing said platen bodily, means for actuating the platen, means including a clamp for holding a work-sheet against the platen, whereby the work-sheet may be adjusted to bear a predetermined relation to 105 the platen, and means for holding the platen against angular displacement with reference to said frame, said work - sheet - adjusting means coöperating with said platen-holding means to hold the work-sheet against displacement when the platen frame is displaced after the platen has been actuated in a writing operation.
- 105 39. In a typewriting machine, the combination with a revoluble platen and a work-sheet thereon, of a clamp for detaining the work-sheet, a latch for detaining the platen, means, including a spring, for moving said 110

latch and said clamp to effective positions, and an auxiliary spring for moving the clamp to effective position.

40. In a typewriting machine, the combination with a revoluble platen, of a clamp for detaining a work-sheet thereon, a latch for detaining the platen, and a single means

for moving the latch and clamp to effective positions.
